(57) **CLAIM**

The ornamental design for the stylus holder, as shown and described.

DESCRIPTION

FIG. 1 is a top and front perspective front view of a stylus holder showing my new design;

FIG. 2 is a bottom and front perspective view thereof;

FIG. 3 is a front view thereof;

FIG. 4 is a rear view thereof;

FIG. 5 is left side view thereof;

FIG. 6 is a right side view thereof;

FIG. 7 is a top view thereof; and,

FIG. 8 is a bottom view thereof.

The hand and stylus depicted in broken line are shown for illustrative purposes only and form no part of the claimed design.
